MULLION CONSTRUCTION

Edmund Peremi, Bayside, N. Y., and Henry Weimann, Brentwood, Mo., assignors, by mesne assignments, to General Bronze Corporation, Garden City, N. Y., a corporation of New York

Original application February 14, 1946, Serial No. 647,560. Divided and this application June 8, 1948, Serial No. 31,808

1 Claim. (Cl. 189—75)

1

This invention relates to a mullion construction for metal windows, the subject matter of the application being divided out of our co-pending application Serial No. 647,560, filed February 14, 1946, now Patent No. 2,473,298, dated June 14, 1949.

An object of the invention resides in the provision of a mullion construction which takes advantage of the flanges on the metal window frame which are used normally when only one frame is set in an opening to accommodate the anchor and seal the window within the opening.

A further object of the invention resides in the provision of a filler strip which is positively secured to the adjacent jambs of two metal frames to secure the frames together, and in the provision of a cover plate which secures and draws the jambs of the frames together by a frictional wedging action.

In the drawing the single figure shows a cross section of the jambs of two adjacent window frames with the filler strip and cover plate securing the same together.

One frame is indicated generally by the reference numeral A, and the other by the reference numeral B, only sections of the frames being shown. Each of these frames includes a parting bead 10 and guide flanges 11 and 12. The guide flanges 11 and 12 with the parting bead form channels 13 for the reception of the side rails of the sash in the manner disclosed in our Patent No. 2,569,386, dated September 25, 1951.

Extending outwardly from the frames are flanges 14 and 15. Each of these vertical flanges 14 is provided with an inwardly extending vertical flange 16 which, when two of the windows are set in abutting relation, abut each other as disclosed in the drawing. Each of the vertical flanges 15 is provided with outwardly extending flanges 17 and inwardly extending flanges 18 which abut each other when two of the windows are set in contiguous relationship.

These inwardly extending flanges 16 and 18 cooperate with the frame anchor when a single window is used, as disclosed in our Patent No. 2,569,386, dated September 25, 1951, and, additionally, they function to align the two frames in the manner explained above when two of the frames are arranged in contiguous relationship.

Extending outwardly from the flanges 11 are

flanges 19 which form a channel 20 therebetween, the channel extending substantially the full length of the jamb, as do the flanges 16, 17 and 18.

5 A filler strip 21, which may be either of wood or metal, is disposed between these flanges 19 and within the channel 20, and is secured to the flanges by suitable means such as screws 22, thus holding the flanges 16 in their abutting relationship and preventing movements thereof.

10 At the opposite side of the window frames a cover plate 23, which is substantially coextensive with the jambs of the frames vertically, is arranged and is provided with a chamfered groove 24 which is substantially coextensive with the 15 cover plate. When the cover plate is applied with the flanges 17 located in the chamfered groove the forcing of the edges of the cover plate into contact with the flanges 12 wedges the flanges 17 in the chamfered groove and draws the flanges 17 and 18 on the two jambs tightly together and maintains them in that position.

Thus with the edges of the filler strip 21 abutting the flanges 14 and the filler strip drawn tightly thereagainst, with the flanges 16 abutting each other, with the flanges 18 abutting each other and the flanges 17 abutting each other, and with the edges of the cover plate 23 tightly engaging the flanges 12 and the flanges 17 wedged within the chamfered groove 24, the adjacent 30 jambs of the two adjacent windows of the metal type will be securely held together and the joint will be covered with weatherproofing strips which also act as finish strips.

We have described the particular construction 35 that is illustrated in the drawing, but it will be realized that some changes may be made in the design without departing from the spirit of the invention or exceeding the scope of the single claim.

40 We claim:

In a metallic window construction, a pair of window frames having hollow vertical jamb members arranged contiguous to each other, inwardly extending vertical flanges on said jamb members 45 arranged in contact with each other at both sides of said jamb members, an outwardly extending vertical flange on each of said jamb members and in spaced relation to each other to form a channel for the reception of a filler strip, a filler strip located in said channel, means securing said filler

strip to both of said jamb members, an outwardly extending vertical flange on the side of each of said jamb members opposite to said filler strip and arranged in contacting relation to each other, and a cover plate bridging said last mentioned flanges and having a chamfered groove therein having beveled faces with which said flanges are frictionally engaged.

EDMUND PEREMI.

HENRY WEIMANN.
